(57) **CLAIM**

The ornamental design for an egg decorating kit, as shown and described.

DESCRIPTION

FIG. 1 is a front perspective view of an egg decorating kit showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of area **9** in FIG. 1; and,

FIG. 10 is an enlarged view of area **10** in FIG. 1.

The broken lines in the figures are for the purposes of illustrating portions of the egg decorating kit, which form no part of the claimed design.
